UNITED STATES PATENT OFFICE.

SAMUEL STEPHENS, OF SOMERVILLE, MASSACHUSETTS, ASSIGNOR TO SAMUEL STEPHENS AND WICKERSHAM QUOIN COMPANY, OF BOSTON, MASSACHUSETTS, A CORPORATION OF MASSACHUSETTS.

LOCKUP DEVICE.

Application filed October 25, 1924. Serial No. 745,797.

To all whom it may concern:

Be it known that I, SAMUEL STEPHENS, a citizen of the United States, and a resident of Somerville, in the county of Middlesex 5 and State of Massachusetts, have invented an Improvement in Lockup Devices, of which the following description, in connection with the accompanying drawings, is a specification, like characters on the drawings representing like parts.

My invention aims to provide an improved lockup device particularly for use by printers, as for locking up a small form in a large chase, for locking a chase in the desired position in the press bed, or like purposes.

In the accompanying drawings showing one illustrative embodiment of my invention:

20 Fig. 1 illustrates a chase having a small form locked up therein by a mechanism embodying one form of my invention;

Fig. 2 is an elevation upon a larger scale of the lockup device shown in Fig. 1;

25 Fig. 3 is an elevation similar to Fig. 2 but viewing the opposite side of the device;

Fig. 4 is a view partially in side elevation and partially in section upon the line 4—4 of Fig. 2;

30 Fig. 5 is a section upon the line 5—5 of Fig. 3; and

Fig. 6 is a detail perspective view of a portion of the locking mechanism.

Referring first to Fig. 1, I have indicated 35 a chase at 1 within which is the relatively small form 2. Said form may be locked in one direction in said chase by any suitable furniture, such as the block 3 and the quoin 4. In the other direction, lengthwise of the 40 chase is illustrated in Fig. 1, said form is confined by an extensible lockup device illustrating one embodiment of my invention.

As best seen in Figures 2 to 5, said lockup 45 includes a pair of relatively movable, telescoping members 5, 6. The outer member 5 comprises a main portion formed as a substantially rectangular tube of pressed steel or other suitable metal and an end portion or base 7 of quoin-like form. Any suitable 50 construction may be employed for said end portion 7 such, for example as the quoin shown and described in my United States Letters Patent 1,470,297, dated October 9, 1923, and which may be operated by a key

inserted at 8 to manipulate the quoin 55 in the usual manner. To adapt said quoin for use in the present connection one of its relatively expansible members is preferably cast with a laterally projecting lug 7' having a driving fit within the end of the tubular member 5.

The other or inner member 6 comprises an elongated metallic element adapted to be received within and longitudinally slidable relatively to said outer or tubular member 5. 65 At its outer end said member 6 is provided with a transverse head 9 to afford a secure bearing at that end of the lockup device. Upon one face of said member 6 I provide a longitudinal groove or channel 10 preferably extending from the head 9 to a point adjacent the opposite end of the member 6 and adapted to receive a pin 11 which projects inwardly from the adjacent face of the member 5. During relative movement 70 of the members 5 and 6 the pin rides in said groove 10 and functions both as a guide and as a stop to limit the outward movement of the member 6 relative to the member 5.

Since the members 5 and 6 may frequently 80 be subjected to very considerable end pressure it is essential to lock them securely in the desired adjusted position with respect to each other and my invention includes improved means for this purpose. Accordingly 85 one of the relatively movable members, herein the member 6, is provided along one side or face with a series of ratchet teeth 12, each tooth therein having a straight face substantially perpendicular to the longitudinal axis of the member 6 and an inclined face. Cooperating with said ratchet teeth is pawl 13 of substantially rectangular form and having on one broad face a relatively short series of correspondingly shaped teeth 90 14.

The member 5 is notched or cut out on its side face adjacent the ratchet teeth 12 to provide an opening 15 through its wall so positioned that the pawl 13 may have a 100 sliding fit therein, said pawl being movable at right angles to the series of ratchet teeth into and out of engagement therewith. Said pawl 13 when engaged with the ratchet teeth seats between the opposed shoulders 105 or abutments 16, 17 formed by the adjacent portions of the member 5.

Any suitable support for the pawl may

be provided whereby the latter may have the rectilinear movement above mentioned and herein I have shown for this purpose the slideable pawl carrier 18 extending across 5 the member 5. Said pawl carrier, as seen in detail in Fig. 6, is provided at one end with an upset portion 19 to which the pawl 13 is removably secured as by means of the screw 20 whereby the pawl may be replaced 10 if desired in case it should become worn. At its opposite end the pawl carrier has a portion bent in the same direction as the portion 19 to provide the operating or finger piece 21.

15 As previously mentioned the pawl and pawl carrier are movable in a straight line at right angles to the longitudinal axes of the members 5, 6, substantially perpendicularly to their path of relative movement and in 20 parallelism with the straight faces of the ratchet teeth. Said pawl carrier is guided by means of a guide recess or groove 22 in one face of the member 5 and in which the carrier has a sliding fit, being retained in 25 position by suitable means, such as the cover plate 23. The depth of said guide groove 22 desirably is such that the pawl carrier lies therein flush with the outer face of the member 5 and the cover plate itself is positioned flatwise against said member to which 30 it is removably secured as by the screws 24, 24, etc.

Normally the pawl 13 is held inwardly and in locking engagement with the ratchet 35 teeth 12 by the coil spring 25 which bears intermediate the inner face of the finger piece 21 and the adjacent side of the member 5 where it is seated in the retaining recess 26.

40 In some instances it is desirable to provide interchangeable members, such as the member 6, of different lengths, in which case the pin 11 may be removed as by driving it out of the member 5 into the hole 27 provided 45 for the purpose in the member 6. The member 6 may then be entirely separated from the tubular member 5 and a like member of different length substituted. In that 50 connection indicating means, such as the window 28, may be provided to afford observation of the position of the member 6 within in the member 5.

It will be understood that the member 6 as herein illustrated may be grasped and 55 extended outwardly with respect to the member 5, the inclined surfaces of the teeth 12 acting to lift the pawl and permit relative movement of the members 5, 6 in one direction. In the opposite direction, however, 60 the flat or straight faces of the teeth afford a firm lock against any relative movement and resist any force tending to telescope the members. It will be noted that the end thrust is taken off from the teeth 12 and 14 65 and is transmitted to and received directly

by the shoulders 16 or 17 against which the pawl abuts.

The slideable locking means having a movement substantially directly perpendicular to the longitudinal axes of the members 5, 6 and parallel to the straight faces of the pawl and ratchet teeth assures rapid and accurate locking action and eliminates substantially all back lash or end play, such as would be occasioned if the pawl 13 were 75 pivotally supported and moved in an arc even of greatest radius possible. The lock-up device may therefore be set more accurately and quickly, while at the same time the rugged construction illustrated renders 80 the device extremely compact, all cumbersome projections such as pivoted levers or the like being obviated.

My invention is not limited to the illustrative embodiment thereof shown and described herein.

Claims—

1. In a printer's lockup device comprising a pair of relatively longitudinally movable members, one adapted to receive the other 90 within it, a longitudinal series of ratchet teeth upon one member, a cooperating pawl having correspondingly shaped teeth, a pawl carrier mounted for sliding movement across one face of the other member, and 95 spring means acting upon said carrier normally maintain said pawl in locking position, whereby said pawl may be moved into and out of locking position along a straight path substantially at right angles to the path of 100 relative movement of said movable members.

2. A lockup device comprising a tubular member having an adjustable base portion, an inner member adapted to be received within and longitudinally movable relatively to said tubular member, and means to secure said members against relative inward movement when in the desired position of adjustment, said means comprising 110 a series of ratchet teeth along one side of said inner member, said teeth having each a straight face and an inclined face, a pawl adapted to engage said teeth through an opening in the adjacent portion of said tubular member, an abutment upon said tubular member to engage said pawl thereby to receive the thrust transferred from the teeth, a pawl carrier extending across one face of 115 said tubular member and mounted for sliding movement along a line parallel to the straight faces of said teeth, a guide for said carrier in the adjacent face of the tubular member, a removable coverplate to retain said pawl carrier in said guide, said pawl being removably connected at one end of 120 said carrier, an operating piece connected to the opposite end of said carrier, and spring means intermediate said operating piece and the adjacent portion of the tubular member 125 130

to hold said pawl normally in engagement with the ratchet teeth.

3. In a printer's lockup device, comprising a pair of relatively longitudinally movable members, one adapted to receive the other within it, a longitudinal series of ratchet teeth upon one member, a cooperating pawl having correspondingly shaped teeth, a spring-pressed pawl carrier, and means upon one face the other of said members supporting said carrier for rectilinear sliding movement across said face so as to move said pawl into and out of engagement with said series of teeth.
- 15 4. In a printer's lockup device comprising a tubular member, a member supported therein for longitudinal movement, a longitudinal series of teeth upon one member and a cooperating spring-pressed locking ele-
- ment upon the other member to effect relatively coarse or approximate adjustment of the overall length of the device, the combination therewith of an adjustable base at one end of said tubular member, said base being formed as a quoin including a pair of relatively expansible, rigid members extending across the end of said tubular member, the inner one of said rigid members having upon its face adjacent the tubular member a securing lug having a driving fit 30 in the adjacent end of said tubular member whereby said quoin-like base is secured in operative position to effect fine adjustment in the overall length of the device.

In testimony whereof, I have signed my 35 name to this specification.

SAMUEL STEPHENS.
